DESIGN.

J. WISHART.

CARPET.

No. 17,862.

Patented Nov. 1, 1887.

UNITED STATES PATENT OFFICE.

JOSEPH WISHART, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,862, dated November 1, 1887.

Application filed August 30, 1887. Serial No. 248,310. Term of patent 3½ years.

To all whom it may concern:

Be it known that I, JOSEPH WISHART, of New York, county and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is adapted for the border of a stair-carpet, and consists of an inner margin

having a row of small ornamental figures. The middle part of my border has large circular flower forms placed at intervals, and between them are groups of small circular flower forms. Small buds and leaves are scattered here and there between the other forms. The border has an outer ornamental margin.

What I claim as new, and desire to secure by Letters Patent, is—

The design for a carpet-border, consisting of the design substantially as shown.

JOSEPH WISHART.
